MICROMETER SCRIBING TOOL

Walter Kozlowski, Irvington, N. J., assignor of
one-half to Peter J. Gaylor, Newark, N. J.

Application June 2, 1948; Serial No. 30,667

2 Claims. (Cl. 33—189)

1

This invention deals with a micrometer scrib-
ing tool and, more specifically, to a combination
micrometer scrib-
ing tool adapted for flat or round
edge surfaces, and capable of being used as a
depth gage, and the like.

The invention will be more readily understood
from the drawings in which Fig. 1 shows a front
view of the complete tool, Fig. 2 a partial side
view and Fig. 3 a partial back view. In Fig. 4
are shown details as side views of the reading cyl-
inder units and the scriber rod cylinder. De-
tailed side views of the scriber rod units and
spac-
er are illustrated in Fig. 5, while Fig. 6
shows a side view and front view, respectively,
of the scriber. Side views of the calibrated cyl-
inder elements are depicted in Fig. 7, while Fig.
8 shows a back view and Fig. 9 a side view of the
adapter for round edges. A cross sectional top
view of the body block is shown in Fig. 10, the
end view being shown in Fig. 11. Similar nu-
merals refer to similar parts in the various fig-
ures.

Referring again to the drawings, numeral 1
represents a block, the forward or front face 62
of which is ground flat to act as a support for
the tool during measuring. Pressed into opening
5 of block 1 as a tight fit is end 9 (Fig. 7) of cyl-
inder 8 which has interior threaded portion
12 on one end and a thin shell on the other. On
cylinder 8 is mounted collar 10 which rests
against block 1 and pressed over cylinder 8 is
tightly fitting calibrated cylinder 11, the inner
bore 14 of which fits snugly against cylinder 8.
The outer surface of cylinder 11 is provided with
calibrations 13 which specify, accurately, the
amount of protrusion of face 41 of scriber 43 past
face 62 of block 1. Hole 66 is provided for in-
serting a circular wrench to turn cylinder 11 on
8 for adjustments when face 41 of scriber 43 is
worn. End bushing 15 with inner threads 16 is
screwed on the outer threads on the end of cyl-
inder 8, by inserting a circular wrench in hole
65, thus keeping calibrated cylinder 11 firmly on
cylinder 8. Inner threads 12 are preferably
spaced 40 to the inch, while the outer ones may
be 60 to the inch.

Hollow scriber rod spindle 24 (Fig. 4) fits into
and rides in cylinder 8 by engaging threads 26
with inner threads 12. Fitting over end 29 of
scriber rod spindle 24 is hollow vernier reading
cylinder 17, the inner surface 18 of which just
barely clears collar 27 separating threaded por-
tions 26 and 28 on spindle 24. Threaded end 28
of spindle 24 projects through narrow opening
19 on vernier cylinder 17, enabling screwing

2

thereon of hollow bushing 22 by means of threads
23, serving as a lock for vernier cylinder 17
which has vernier calibrations 20 around its free
peripheral edge; and knurled portion 21 for fa-
cilitating turning of the cylinder.

End 29 of spindle 24 is undercut to fit counter-
bore 37 of spacer 34 (Fig. 5). Scriber rod 31 on
which rides scriber 43 (which is kept from leav-
ing the end of rod 31 by collar 32), fits into
scriber rod spindle 24. Threaded end 33 of rod
31 projects through cylinder 17 and bushing 22.
On end 33 are mounted spacers 34 which may
be exactly 1" long and which are counterbored
at 37 and undercut at 36, the latter to fit an ad-
jacent counterbore in a spacer or counterbore 39
of lock nut 38; the inner threads 40 of which en-
gage threaded end 33 of scriber rod 31, thereby
keeping tight the whole scriber rod assembly.
The spacers 35, serve to lengthen measured por-
tion 24 (Fig. 1) of scriber rod spindle 24 when
they are transferred from position 35 in Fig. 1.
This is done by unscrewing lock nut 38, remov-
ing spacer 35', slipping out scriber 43 and rod 31
and inserting on rod 31 the spacer 35'.

End 25 of spindle 24 (Fig. 4) is undercut to al-
low fitting therein of end 44 of scriber 43 (Fig. 6).
Scriber 43 (Fig. 6) is provided with wheel por-
tion or face 41 in the edge of which are cut teeth
42 used for the scrib-
ing operation.

Steel scriber block 1 has side holes 60 and 61,
threaded at their free ends to engage threads on
adjusting screw 3 and lock screw 2, respectively.
Brass thrust plugs 6 and 7 are provided to seat
against scriber rod spindle 24 and thus enable
locking of the spindle at any setting.

When the tool is used for accurate scrib-
ing on a flat surface, knurled end 21 of cylinder 17 is
turned, which in turn propels scriber rod spindle
24 holding scriber rod 31 from the end of
which projects scriber 43 with scrib-
ing teeth 42. When the desired projecting distance is obtained
(as read from scale 13 and vernier 20), spindle 24
is locked in the cylinders by tightening lock
screw 2. The tool may be then used for scrib-
ing, employing face 62 of block 1 as the guide.

If a round edged surface is to be scribed, center
head 45 is mounted on head 1 and fastened there-
on by means of lock screws 55. Then, cylinder
17 is turned until scriber face 41 just touches the
edge of the surface to be scribed (the surface
being inserted in the 90° angle made by sides 48
and 49 of members 46 and 47). The reading is
taken on scale 13 and spindle 24 is then screwed
out forwardly until the desired distance within
55 the surface to be scribed is reached (as read from

scale (3). Thereafter, the spindle 24 is locked by screw 2 and scribing is done as heretofore outlined. The scribe 43 may be substituted by a pin to act as a depth gage.

The tool of the present invention has many advantages over those now on the market. For example, it may be used efficiently for straight or circular surfaces. Also, if the surface to be scribed, or adjacent surfaces, have ridges or recesses, these will not interfere with the scribing operation, since guiding is done at the edge and the scribe projects from spindle 24 which then may straddle protuberances, ridges, etc. and also allow scribing edge 42 to sink into ridges without interfering with the scribing.

It has been found desirable to allow collar 10 (Fig. 7) to stand on cylinder 8 far enough away from the rear face of block 1 to enable collared lip 51 on adapter 45 to rest against it (as in Fig. 1) and thus act as a positioner for lip 51 when surface 50 rests tightly on face 62 of block 1. The forward end of sleeve or cylinder 11 butts up against collar 10 (Fig. 7). Numeral 4 represents a chamfered opening in the front or guiding face of base 1 into which scribe 43 recedes when it is screwed back as far as possible. Numeral 52 represents the cut-away portion at the bottom of the V of the center head 45 through which the scribe emerges, while numeral 54 represents the threaded hole in which screws 55 are inserted.

I claim:

1. In a micrometer scribing tool employing a block having a flat forward guiding surface, a central opening through said block perpendicular to said guiding surface, a hollow cylinder fitted at one end into an end of said opening opposite said guiding surface, and having internal threads, a calibrated cylinder mounted on said cylinder so as to ride therewith, a hollow scribe rod spindle having external threads riding on the internal threads of the hollow cylinder, a scribe rod fastened inside said scribe rod spindle and riding therewith, the forward end of which projects through said block and on which is attached the scribe, and a vernier reading cylinder mounted

over said calibrated cylinder and fastened to the rearward end of said spindle so as to ride therewith, said vernier cylinder being turned to propel said scribe, said tool also employing a V-shaped center head for use on circular edges, the V being made of forwardly projecting prongs, 90° apart, the improvement comprising a collared mounting on the bottom of the V of the center head, for central positioning on said block so that the scribe projects from the bottom of the V between the two prongs thereof, engaging means on said mounting for engaging said center head on said block in removable relation thereto, and said scribe having a circular scribing edge disposed completely around the scribe rod spindle.

2. A micrometer scribing tool according to claim 1 in which at least one side of the block carries a thrust plug, and at least one lock screw to impose thrust on a thrust plug so as to lock said spindle in set position.

WALTER KOZLOWSKI.
